(57) **CLAIM**

The ornamental design for a passengers' compartment for games and for car including toy-car, motor car, replica car and scale-model-car, as shown and described.

DESCRIPTION

FIG. 1 is a partial front view of the passengers' compartment for games and for car including toy-car, motor car, replica car and scale-model-car showing my new design taken along line I—I in FIG. 3;

FIG. 2 is a partial rear view thereof taken along line II—II in FIG. 3;

FIG. 3 is a top view thereof;

FIG. 4 is a bottom view thereof;

FIG. 5 is a partial left side view thereof taken along line V—V in FIG. 3;

FIG. 6 is a partial right side view thereof taken along line VI—VI in FIG. 3; and,

FIG. 7 is a perspective view thereof.
